CLAIM

I claim the ornamental design for the multifunction kitchen console, as shown and described.

DESCRIPTION

2. Multifunction kitchen console

Fig. 2.1 is a front view of the multifunction kitchen console showing my new design;

Fig. 2.2 is a back view thereof; and

Fig. 2.3 is a right side view thereof.

The broken line showing of portions of the multifunction kitchen console depicts environment and forms no part of the claim; the broken lines immediately adjacent surfaces shown in solid lines depict boundaries of the claim.
